ATTORNEY

UNITED STATES PATENT OFFICE.

ANDREW C. LATHROP, OF YANTIC, CONNECTICUT.

CLOSURE FOR BOTTLES AND OTHER RECEPTACLES.

1,348,014.

Specification of Letters Patent. Patented July 27, 1920.

Application filed March 14, 1918. Serial No. 222,418.

To all whom it may concern:

Be it known that I, ANDREW C. LATHROP, a citizen of the United States, residing at Yantic, in the county of New London and

5 State of Connecticut, have invented certain new and useful Improvements in Closures for Bottles and other Receptacles, of which the following is a specification.

10 My invention relates to new and useful improvements in bottle closures and more particularly to the type which is impossible to replace to its former position in the bottle neck, thereby providing means for the detection of an unauthorized opening of the

15 bottle.

An important object of my invention is to provide a device having its parts constructed of such irregular shape that it will be practically impossible to correctly position all the various parts to their respective 20 positions after they have been disassembled to allow the dispensing of the contents of the bottle.

Another object of my invention is to provide a device including means whereby one 25 part of the invention will be securely held in the neck of a bottle with its upper portion flush with the top edges of the bottle neck thereby preventing unauthorized persons 30 from removing said part from the neck of the bottle.

Another object of my invention is to provide a device which is strong, durable, inexpensive to manufacture, and is efficient in 35 practice.

Other objects and advantages of my invention will be apparent during the course of the following description.

In the accompanying drawings forming a 40 part of the description and wherein like numerals are employed to designate like parts throughout the same,

Figure 1 is a top plan view of a bottle with my invention applied thereto.

45 Fig. 2 is a vertical sectional view from the upper portion of a bottle and my invention in its proper position in the bottle neck.

Fig. 3 is a bottom plan view of the retaining member.

50 Fig. 4 is a top plan view of the stopper, and

Fig. 5 is a horizontal sectional view taken on the line 5—5 of Fig. 2.

55 In the drawings wherein for the purpose of illustration is shown a preferred embodiment of my invention, the numeral 1 design-

nates the body portion of an ordinary bottle, having its neck 2 provided with internal screw threads, at the lower end of which the neck is provided with a plurality of circumferential notches 3 as more clearly shown in Figs. 2 and 5.

A retaining member 4 is externally screw threaded for engagement with the threaded neck of the bottle, and is adapted to be 65 screwed into said neck until the top of this part is flush with the top edges of the neck. This arrangement prevents the removal of the retaining member by unauthorized persons. The member 4 is provided with a 70 circular bore 5 extending from the bottom thereof and gradually diminishing in diameter as at 6 adjacent the top of said bore. The bore through the top of this member is not circular in cross-section as at its lower 75 parts, but is square as at 7 for a purpose which will presently appear. An air opening 8 is provided in the top of this retaining member and communicates with the tapered portion 6 of the bore, for admitting 80 air into the bottle while the contents are being dispensed. In the outer periphery of the member 4, adjacent its lower end, I provide a recess or notch 9 having one of its walls arranged radially of the member 4 to 85 provide the seat to which I solder a flat spring 10 with its outer end projecting beyond the periphery of the retaining member for engagement with the notches in the neck of the bottle, thereby preventing reverse rotation of the retaining member after 90 it has attained its proper position in the neck of the bottle.

Adapted to operate in the bore through the retaining member, is a cork stopper 11, 95 and is of such configuration and size that it will be snugly received in said bore. The upper part 12 of the stopper is made square in cross-section and is adapted to extend through the opening 7 in the top of the 100 rectangular member and project a substantial distance beyond the top thereof. It will be noted that the tapered portion of the stopper normally closes the air opening 8 and prevents admission of air into the 105 bottle.

In operation the retaining member together with the stopper 11 in its proper position, is screwed down into the neck of the bottle until the top of said member is flush 110 with the top of the bottle neck, and the spring 10 engages one of the notches 3. It

will now be impossible to remove either member since reverse rotation of the member 4 is prevented by the spring 10 in engagement with its respective notch and the 5 largest portion of the stopper is beneath the opening 7 and is in close engagement with the upwardly converging walls 6 of the bore in the retaining member. When it is desired to empty the contents of the bottle, the 10 stopper 11 is forced inwardly by pressing upon the portion 12 until it is entirely disengaged from the retaining member. This 15 operation also uncovers the air inlet opening 8 and permits air to enter the bottle and facilitate ready dispensing of the contents. By reason of the irregularity in shape of the stopper and its seat or bore through the retaining member, the contents will readily pass through the retaining member to make 20 its exit. It will be seen that it is quite impossible to replace the stopper 11, since it would be a task to get the squared portion 12 into alignment with the squared opening in the retaining member so that this portion 25 could be pulled through said opening for properly positioning the remainder of the stopper in relation to the bore through the retaining member.

It is to be understood that the form of my 30 invention herewith shown and described is to be taken as a preferred example of the same and that various changes in the shape, size and arrangement of parts may be resorted to without departing from the spirit 35 of the invention or the scope of the subjoined claims.

Having described my invention I claim:

1. A closure including a retaining member having a circular bore therethrough, the upper walls of said bore converging upwardly, the uppermost end of said bore being square, and a buoyant stopper having its body portion the same shape as said bore to be snugly received therein, the upper portion of said stopper being square to be engaged by the square portion of the bore, and extended thereabove. 40 45

2. In combination with a bottle, of a retaining member secured to the neck thereof and having a round bore therethrough, the upper walls of said bore converging upwardly to form a restricted passage, the upper end of restricted passage being square, and a stopper of the same shape as the bore and restricted passage to be snugly 50 55 received therein, when the bottle is sealed.

3. In combination with a bottle neck, a retaining member having a bore therethrough, the upper walls of which converge upwardly, said member being further provided with an air opening which terminates at the converging portion of the bore, and a stopper having a portion thereof tapered to fit the converging portion of the bore to close the air opening when the bottle is 60 65 sealed.

In testimony whereof I affix my signature in presence of two witnesses.

ANDREW C. LATHROP.
